(57) **CLAIM**

The ornamental design for a gaming table, as shown and described.

DESCRIPTION

FIG. 1 is a top, front perspective view of a gaming table, showing my new design;

FIG. 2 is a front elevational view thereof;

FIG. 3 is a rear elevational view thereof;

FIG. 4 is a left-side elevational view thereof, the right-side elevational view being a mirror image;

FIG. 5 is a top plan view thereof; and,

FIG. 6 is a magnified portion thereof, as designated in FIG. 1.

The broken lines showing of speakers are for the purpose of illustrating portions of the gaming table and form no part of the claimed design. The broken lines around the designated magnified portion do not form part of the claim.
